CLAIM

I claim the ornamental design for an oscillating massage belt, as shown and described.

DESCRIPTION

FIG. 1 is a top view of an oscillating massage belt showing my new design;

FIG. 2 is a front view thereof;

FIG. 3 is a bottom view thereof;

FIG. 4 is a rear view thereof;

FIG. 5 is a right side view thereof;

FIG. 6 is a left side view thereof;

FIG. 7 is a rear perspective view thereof; and,

FIG. 8 is a front perspective view thereof.

The broken line showing of visible environmental structures is for illustrative purposes only and forms no part of the claimed design.

The broken lines are for illustrative purposes only and form no part of the claimed design.
